(57) CLAIM

The ornamental design for a liquid fragrance container as shown and described.

DESCRIPTION

FIG. 1 is a right perspective view of a liquid fragrance container showing my new design;

FIG. 2 is a front view thereof;

FIG. 3 is a back view thereof;

FIG. 4 is a top view thereof; and,

FIG. 5 is a bottom view thereof.

The dash-dash lines in the figures show elements that form no part of the claimed design.

1 Claim, 5 Drawing Sheets
